UNITED STATES PATENT OFFICE.

FRANK W. GERLACH AND MILTON M. CULP, OF FRANKLIN, OHIO.

COIN-CONTROLLED VENDING-MACHINE.

No. 896,101.

Specification of Letters Patent.

Patented Aug. 18, 1908.

Application filed May 7, 1906. Serial No. 315,606.

To all whom it may concern:

Be it known that we, FRANK W. GERLACH and MILTON M. CULP, citizens of the United States, residing at Franklin, in the county of 5 Warren and State of Ohio, have invented certain new and useful Improvements in Coin-Controlled Vending-Machines; and we do declare the following to be a full, clear, and exact description of the invention, such as 10 will enable others skilled in the art to which it appertains to make and use the same.

This invention relates to improvements in coin controlled cigar vending machines.

The object of the invention is to provide an 15 improved construction of machines of this character, whereby the operating mechanism will be simplified and the number of parts of said mechanism decreased, thereby lessening the possibility of the machine getting out of 20 order and providing a strong, durable and reliable vending machine for cigars or other articles.

A further object is to provide means actuated by the operation of the machine to close 25 the coin slot after the delivery of the last cigar in the machine.

With the above and other objects in view, the invention consists of certain novel features of construction, combination and arrangement of parts, as will be hereinafter described and claimed.

In the accompanying drawings:—Figure 1 is a horizontal sectional view, taken above the discharge plate of the machine; Fig. 2 is 35 a detail sectional view through a portion of the casing and the discharge plate, showing the mechanism for holding and releasing said discharge plate at one side of the coin chute; Fig. 3 is a similar view, showing the construction of the slot closing mechanism arranged on the opposite side of the coin chute; Fig. 4 is an enlarged detail view of a portion of the apparatus.

Referring more particularly to the drawings, 1 denotes the casing of the machine. In the body of the casing is arranged an especially constructed box 3 adapted to contain the desired number of cigars and to support the same in position to be delivered one at a 45 time by the vending mechanism. The box 3 is preferably of a flat elongated construction sufficiently deep and wide to contain a single layer or tier of cigars.

In placing the box 3 in the casing for use, 50 the same is adapted to engage or rest against

an inclined supporting board or plate 5 arranged in the body of the casing. The lower open end of the box 3 when thus arranged in the casing is supported in a rectangular frame 6 secured to the board 5, said frame 60 being provided at each end with spring metal clamping fingers 7, which engage the side edges of the box and securely hold the same in place. The lower end of the box 3 is disposed immediately above a discharge plate 8 65 which is slidably mounted in guideways 9, on the sides of the casing, as shown. In the plate 8 is formed a longitudinally disposed discharge slot 10 through which the cigars from the box 3 are discharged when the plate 70 8 is pushed back to bring said slot beneath the end of the box and the frame 6, as will be understood. The plate 8 is normally thrown forwardly and held in an inoperative position against stops 12 on the sides of the casing by 75 means of coil springs 13 which are connected at one end to the forward edge of the plate and at the opposite ends to the sides of the casing, as shown.

Pivots mounted in a pair of upwardly 80 projecting arms 14 on the frame 6 is a bail-like retainer or detent 15, said detent being here shown as formed of a single piece of wire bent midway between its ends to form a rectangular, inwardly-curved stop or cigar 85 engaging portion 16 which is adapted to project into the opening in the lower end of the box 3 and to pass between the lower cigar and the one next above it in said box 3 when the discharge plate 8 is operated. The detent rod or wire 15 is provided on one end with a right angularly-bent crank arm 17, to the lower end of which is connected a coil spring 19, the opposite end of which projects through a hole in the plate or board 5 and is 90 connected to the inner edge of the discharge plate, whereby when said plate is pushed inwardly to bring the discharge slot therein beneath the end of the box 3, said detent will 95 be rocked to cause the stop or cigar engaging portion 16 to pass between the lowermost and the next adjacent cigar, thereby preventing more than one cigar from passing through the slot.

The vending mechanism comprises a plunger 20, which is slidably mounted in the front side of the machine, and has its inner end working through the lower rear end of a coin chute 21, the forward upper end of which communicates with a coin slot 22 formed in 110

the front of the machine, as shown. The lower rear end of the coin chute 21 is bifurcated, as shown at 24, and in said bifurcated portion is adapted to slide the inner edge of 5 the discharge plate 8, said edge being reduced at its point of engagement with the coin chute, thereby permitting the same to freely enter the bifurcated end of the chute. The plunger 20 is provided with an annular 10 shoulder, by means of which the inward movement of the same is limited. A supporting bracket 25 is arranged on the inner side of the front plate of the casing through which the inner end of the plunger is adapted 15 to slide. Around said inner end of the plunger between the shoulder thereon and the bracket 25 is arranged a coil spring, the tension of which is exerted to normally hold the plunger rod out in a retracted position. The 20 limited movement of the plunger 20 prevents the same from pushing the discharged plate back to an operative position without the insertion of a coin in the chute 21, the coin when dropped in the chute being adapted to 25 pass to a position between the inner end of the plunger and the adjacent reduced portion of the discharge plate in the bifurcated end of the chute, thereby practically increasing the length of the plunger sufficiently to enable 30 the same to force the discharge plate back far enough to bring the slot 10 therein beneath the end of the box 3, which will permit the lowermost cigar to fall through said slot and be delivered to the purchaser. The bottom 35 of the bifurcated end of the coin chute is provided with a discharge opening 26, through which the coin will drop after the discharge plate has been brought to an operative position.

40 In order that the discharge plate may be held in an operative position until the coin has been discharged through the opening 26, a detent or catch 27 is provided. Said detent is here shown and is preferably in the form of 45 a lever pivotally mounted on one side of the coin chute and provided with a forwardly projecting plate engaging end 28, in which is formed a notch 29 to engage the reduced edge of the plate 8 when the latter is forced to an 50 operative position. The rearwardly projecting notched end of the detent lever 27 is of less length and therefore lighter than the forwardly-projecting end of the same, and is consequently overbalanced by said forward 55 end to cause said notch to automatically engage the edge of the plate 8, as will be understood. The lower edge of the forwardly-projecting end of the detent lever 27 is formed at an angle or inclined downwardly toward 60 its forward end, as shown at 30, said inclined edge being adapted to be engaged by a bifurcated or forked releasing plate 31 which is carried by the plunger 20 and is arranged thereon adjacent to the annular shoulder of 65 the plunger, so that when the plunger is

pushed forward or inward the outer end of the lever can descend and the inner end will rise and its notch will engage with the plate 8, but when the spring forces the plunger outwardly after operating the discharge plate 31, said releasing plate will engage the lower inclined edge of the detent lever 27 forcing the same upwardly and the notched end 28 of the same downwardly, thereby disengaging the notch from the operating plate, which will permit 75 the springs 13 to retract the plate back into its normal position.

On the opposite side of the coin chute from that on which the detent lever 27 is mounted is arranged a slot closing mechanism by 80 means of which the insertion of a coin in said slot will be prevented when the last cigar has been discharged from the machine. The slot closing mechanism is here shown and is preferably in the form of a ratchet wheel 32 pivotally mounted upon the side of the coin 85 chute. On the outer side of the ratchet wheel is secured a spring or arm 33, on the outer end of which is formed a right angular, inwardly-projecting stop lug or detent 34 90 which projects through an opening 35 in said wheel and normally bears against a circular plate 36 arranged on the side of the coin chute. Said arm and lug are carried around by the movement of the wheel until the lug 95 34 is brought opposite to aligned openings 37 in the coin chute, at which time the spring arm will force the lug through said openings and across the slot, thereby preventing the insertion of a coin therein. The teeth on the 100 wheel 32 are adapted to be engaged by a pawl or other suitable operating mechanism 38, which is slidably mounted in the bracket 25 and is connected to the forward edge of the operating plate 8, so that at each forward 105 movement of said plate when operated to discharge a cigar will cause said pawl to engage the teeth and turn the wheel a certain distance, the teeth on said wheel being arranged so that when the discharge plate 8 has been 110 operated, the same number of times as there are cigars in the machine the stop lug or detent 34 on the spring arm or plate will be brought opposite to the aligned openings 37 in the coin chute through which said lug will be 115 projected thereby stopping or preventing the insertion of a coin, as hereinbefore described.

Beneath the coin discharge opening in the chute 21 is arranged a drawer or coin receptacle 39, into which the coins will drop and 120 by means of which the same are safely held until removed by the proper authority.

From the foregoing description, taken in connection with the accompanying drawings, the construction and operation of the invention will be readily understood without requiring a more extended explanation.

Various changes in the form, proportion and the minor details of construction may be resorted to without departing from the prin- 130

ciple or sacrificing any of the advantages of this invention, as defined by the appended claims.

Having thus described our invention, what we claim as new and desire to secure by Letters-Patent, is:—

In a vending machine, a case, delivery plate reciprocally mounted therein a perforated coin chute, a perforated toothed wheel adjacent thereto, a spring on the wheel with its free end provided with a lug, and a pawl

on the plate for engaging with said wheel and retaining it until said lug is in position to project through all of said perforations.

In testimony whereof we have hereunto set our hands in presence of two subscribing witnesses.

FRANK W. GERLACH.
MILTON M. CULP.
